The ornamental design for the fence connector, as shown and described.

DESCRIPTION

FIG. 1 is a perspective view of the fence connector of the present invention;

FIG. 2 is a front elevational view of the fence connector of FIG. 1;

FIG. 3 is a left side elevational view of FIG. 2, the right side elevational view being a mirror image thereof;

FIG. 4 is a top plan view of FIG. 2, the bottom plan view being a mirror image thereof;

FIG. 5 is a perspective view of a second embodiment of the fence connector of the present invention;

FIG. 6 is a front elevational view of the fence connector of FIG. 5;

FIG. 7 is a left side elevational view of FIG. 6, the right side elevational view being a mirror image thereof; and,

FIG. 8 is a top plan view of FIG. 6, the bottom plan view being a mirror image thereof.
